United States Patent

Des. 236,588
Patented Sept. 2, 1975

236,588

MILK CASE

Albert Trapani, Merrick, N.Y., assignor to Wood
Packing Box Company, Brooklyn, N.Y.

Filed Dec. 26, 1973, Ser. No. 427,678

Term of patent 14 years

Int. Cl. D9—03

U.S. Cl. D9—177

FIG. 1

FIG. 2

← 5

FIG. 3

← 6

FIG. 4

← 6

FIG. 5 FIG. 6

FIG. 1 is a top plan view of a milk case, showing my new design;

FIG. 2 is a side elevational view, the opposite side being the same in appearance as the side shown;

FIG. 3 is a bottom plan view thereof;

FIG. 4 is an end elevational view, the opposite end being the same in appearance as the end shown;

FIG. 5 is a sectional view taken substantially along line 5-5 of FIG. 2; and

FIG. 6 is a sectional view taken substantially along line 6-6 of FIG. 4.

I claim:

The ornamental design for a milk case, substantially as shown and described.
